TRIPOD

Alfred Schimpf, Basel, Switzerland, assignor to H. Heer
& Cie, Olten, Switzerland

Filed July 25, 1972, Ser. No. 274,918

Claims priority, application Switzerland May 9, 1972

Term of patent 14 years

Int. Cl. D16—05

U.S. Cl. D61—1 G

FIG. 1

FIG. 2

FIG. 3

FIG. 4

FIG. 5

FIG. 1 is a side perspective view of a tripod showing my new design with the legs partially telescopically extended and with such legs in an intermediate spread-apart position, the opposite sides being substantially identical thereto;

FIG. 2 is a top plan view thereof;

FIG. 3 is a bottom plan view thereof;

FIG. 4 is an enlarged sectional view of the top portion thereof;

FIG. 5 is a side elevational view of the tripod of FIG. 1 in a fully collapsed or folded position.

I claim:
The ornamental design for a tripod, as shown and described.
